UNITED STATES PATENT OFFICE

WILLIS P. THOMAS, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed July 2, 1923. Serial No. 649,140.

This invention relates to boiler cleaners and particularly relates to devices for loosening slag deposits from the parts of boilers.

It is the object of the invention to effect the sudden cooling and contraction of slag deposits upon the tubes or other parts of a boiler preferably by a cooling discharge of water upon such deposits, such contraction having the effect of loosening the slag completely from the boiler parts or effecting a sufficient loosening to permit a subsequent ready removal thereof by steam jets.

In the drawings:

Figure 1 is a view in side elevation of a tubular boiler equipped with the improved cleaner;

Figure 2 is a sectional view on line 2—2 of Figure 1, showing the slag removing means engaged with the lowermost row of tubes;

Figure 3 is a cross section on line 3—3 of Figure 2;

Figure 4 is a section on line 4—4 of Figure 2.

In these views, the reference character 1 designates a bank of boiler tubes, 2 designates the boiler wall and 2 is the fire box of the furnace, the hot gases from which flow primarily beneath said bank of tubes in the first pass of the boiler. Because of the relatively close proximity of the lowermost row 1^a of the tubes to the flames and hot gases, accumulation of slag upon the tubes 1^a is relatively rapid as compared to the remaining tubes of the bank. This accumulation, unless removed at proper intervals, will within a comparatively short period of time completely block the space between adjacent tubes of the row interfering with circulation of the gases and subjecting said tubes to a continuous high temperature that is detrimental. As a remedy for this defect, the invention mounts upon each of the tubes 1^a a flattened fluid pipe 3 having cylindrically convex underfaces to conform to the curvature of the engaged tubes. Each of said pipes is of a width to project laterally somewhat beyond the seat forming surface of the supporting boiler tube and a row of fluid outlets 3^a opens downwardly in each of said projecting portions. Thus fluid, such as water

discharging from the pipes 3 is adapted to flow down the sides of the boiler tubes 1^a to the underfaces of said tubes exercising a cooling effect upon any slag deposits that may adhere to said surface. The pipes 3 are supplied with slag removing fluid, such as water from a header 4 which has connections to corresponding ends of said pipes, each of said connections comprising aligned nipples 5 welded respectively to the header 4 and respective pipe 3 and connected by a coupling 6. 7 designates a water or like fluid supply pipe leading from any suitable source to the header 4 and 8 is a pipe through which a cleaning fluid, such as steam may be admitted to said header. 9 designates an ordinary steam jet blower having for its primary function the removal of soot from the bank of tubes 1.

In the use of the described invention, at predetermined intervals, water is admitted by way of the pipe 7 and header 4 to the pipe 3 discharging from the latter through the openings 3^a upon the lower row of boiler tubes. The latter openings are sufficiently close adjacent so that the surface of the tubes 1^a upon which the slag collects will be subjected to a cooling water flow. The sudden cooling and resultant contraction of any slag deposits upon the tubes 1^a resulting from this flow of water loosens said deposits to such an extent that they will either at once drop from the tubes or may be readily blown from the tubes by a subsequent discharge of steam. This subsequent discharge may be effected either by supplying steam to the pipes 3 after cutting off the water supply thereto or may result from an operation of ordinary blower units, one of which is indicated at 9. For holding each pipe 3 firmly in engagement with the corresponding tube 1^a it is preferred to insert wedges 10 between the pipes 3 and the overlying boiler tubes 1.

Wherever the term "gas" is used in the specification and claims, this word is to be construed as covering any gaseous fluid such as steam, air, and the like.

What I claim as my invention is:

1. The method of removing slag deposits

from a boiler part located with respect to the combustion chamber so as to be subjected to the accumulation of slag consisting in introducing a cooling liquid in contact with the slag.

10 2. The method of removing slag deposits from a boiler part located adjacent the combustion chamber so as to be subjected to the accumulation of slag consisting in introducing water in contact with the slag while the slag is relatively hot from operation of the boiler.

15 3. The method of removing slag from a boiler part which consists in initially introducing a cooling liquid into contact with the slag to contract the slag and loosen the same and subsequently introducing a gas under pressure into contact with the loosened slag to blow the same from the boiler part.

20 4. The method of removing slag from a boiler part which consists in initially discharging water into contact with the slag to contract the slag and loosen the same and subsequently discharging steam under pressure 25 into contact with the loosened slag to blow the same from the boiler part.

In testimony whereof I affix my signature.
WILLIS P. THOMAS.
